US00D980669S

(12) **United States Design Patent** (10) **Patent No.:** **US D980,669 S**
(45) **Date of Patent:** **** Mar. 14, 2023**

(54) **JUICE DISPENSER**

(71) Applicant: **SHENZHEN DENORGIN TECH. CO., LTD.**, Shenzhen (CN)

(72) Inventor: **Rongqiang Shi**, Shenzhen (CN)

(73) Assignee: **SHENZHEN DENORGIN TECH. CO., LTD.**, Shenzhen (CN)

(**) Term: **15 Years**

(21) Appl. No.: **29/786,264**

(22) Filed: **May 31, 2021**

(30) **Foreign Application Priority Data**

Dec. 1, 2020 (EM) 008301063-0002

(51) **LOC (14) Cl.** **31-00**

Assistant Examiner — Arva P Adams

(57) **CLAIM**

The ornamental design for a juice dispenser, as shown and described.

DESCRIPTION

FIG. 1 is a perspective view of a juice dispenser showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and,

FIG. 10 is an enlarged view of portion 10 shown in FIG. 2. The broken lines in the drawings depict portions of the juice dispenser that form no part of the claimed design.

1 Claim, 10 Drawing Sheets
